E. A. F. OLSTEAD.

Car-Track Clearer.

No. 64,695.

Patented May 14, 1867.

United States Patent Office.

EDWARD A. F. OLMSTEAD, OF NEW YORK, N. Y.

Letters Patent No. 64,695, dated May 14, 1867.

IMPROVED SWEEPING MACHINE FOR RAILROADS.

The Schedule referred to in these Letters Patent and making part of the same.

TO ALL WHOM IT MAY CONCERN:

Be it known that I, EDWARD A. F. OLMSTEAD, of the city, county, and State of New York, have invented a new and useful improvement in Railroad Sweepers; and I do hereby declare that the following is a full, clear, and exact description thereof, which will enable others skilled in the art to make and use the same, reference being had to the accompanying drawings, forming part of this specification, in which—

Figure 1 is an end view of my improved sweeper, part being broken away to show the construction; and

Figure 2, a bottom view of one end of the same.

Similar letters of reference indicate corresponding parts.

My invention has for its object to improve the construction of my railroad sweeper, patented July 10, 1866, and numbered 56,256, so as to make its operation more satisfactory and effective, and in making the levers, by means of which the broom is raised and lowered, of exactly the same length, the whole being constructed and arranged as hereinafter more fully described.

A is the platform; B, the axles; C, the wheels, and D are scrapers attached to the end of the platform A, and which are raised and lowered by the levers E pivoted to the standard F. G are the brooms, which are attached to and operated by the shaft H, to the inner end of which is attached a bevel gear-wheel, I, the teeth of which mesh into the teeth of the bevel gear-wheel J attached to the axle B. K is a frame, surrounding the bevel gear-wheels I and J, and having holes through it, through which pass the axle B and the broom-shaft H, and which forms the bearing for the inner end of said broom-shaft. The frame K keeps the gear-wheels I and J in proper operating position with respect to each other, however much the broom may be raised or lowered. M and L are the levers by means of which the broom is raised and lowered. The levers L and M are made of exactly the same length, so that when their inner ends are raised or lowered the same distance, the ends of the broom-shaft H will be raised or lowered equally. The levers L and M are pivoted to supports N upon the upper side of the platform A, and their inner ends are pivoted to each other and to a block or stirrup, O, working in the slotted support P. The pivoting-pin, by which the levers L and M are pivoted to each other and to the block O, passes through slots in the ends of the said levers, and also through vertical slots in the support P, so that all the said parts may be kept in their proper relative positions while being raised and lowered. The inner ends of the levers L and M are raised and lowered to adjust the position of the broom, by means of a hand-screw Q, passing down through a stationary nut formed in or attached to the upper end of the support P, and its lower end is swivelled to the block O, to which the ends of the levers L and M are pivoted. The outer end of the lever M is connected by a rod, R, to the outer end of the shaft H, or to journal-box of the outer end of said shaft. The outer end of the lever L is connected by a rod, S, to that end of the frame K in which the bearings of the shaft H are formed. But as the frame K is pivoted to the axle B, raising or lowering the inner part of the said frame will change the relative positions of the bearings of the two ends of the shaft H, causing it to bind, and thus impeding its working properly. To remedy this I form a universal joint, T, in the shaft H, between the frame K and the broom G, so that the said shaft may operate freely, however much the end of the frame K may be raised or lowered.

I claim as new, and desire to secure by Letters Patent—

The construction, and arrangement of the levers L, M of the same length, their inner ends slotted and pivoted together, and to the stirrup O working vertically in the slotted support P, and adjusted by means of the hand-screw Q, said levers near their outer ends pivoted to the supporter N upon the platform A, and their outer ends pivoted to the rods R, S, attached to the ends of the shaft K, respectively, whereby the said shaft and broom G are raised or lowered, substantially as herein set forth for the purpose specified.

The above specification of my invention signed by me this 28th day of January, 1867.

E. A. F. OLMSTEAD.
